(57) **CLAIM**

The ornamental design for a lighting fixture, as shown and described.

DESCRIPTION

FIG. 1 is a front view of the lighting fixture; the back view of the lighting fixture is identical to the front view;

FIG. 2 is a bottom view thereof;

FIG. 3 is a top view thereof;

FIG. 4 is a left side view thereof, the right side view thereof is identical to the left side view;

FIG. 5 is a top perspective view thereof; and,

FIG. 6 is a bottom perspective view thereof.

The broken lines shown on the drawings depict the boundary of the lighting fixture and form no part of the claimed design.
